UNITED STATES PATENT OFFICE.

ERNEST OLD, OF HAWLEY, TEXAS.

CUSPIDOR HANDLE AND CARRIER.

1,071,457.

Specification of Letters Patent.

Patented Aug. 26, 1913.

Application filed April 9, 1912. Serial No. 689,525.

To all whom it may concern:

Be it known that I, ERNEST OLD, a citizen of the United States, residing at Hawley, in the county of Jones and State of Texas, have 5 invented certain new and useful Improvements in Cuspidor Handles and Carriers, of which the following is a specification.

This invention relates to improvements in devices for lifting and carrying cuspidors 10 or the like.

The principal object is to provide a simple device of this character, which is capable of being readily adjusted to different size cuspidors or vessels of like character.

15 Another object is to provide means on the device to prevent the cuspidor from slipping while being carried.

Other objects and advantages will be apparent from the following description and 20 with particular reference to the accompanying drawings.

In the drawings: Figure 1 is a top plan view of the device, Fig. 2 is an end view, Fig. 3 is a longitudinal section on the line 25 3—3 of Fig. 1, Fig. 4 is a vertical transverse section on the line 4—4 of Fig. 1.

Referring particularly to the drawings, the device includes a handle 10, consisting of the sections 11 and 12, in the abutting face 30 of each of which is formed a longitudinal channel 13, which when the sections are secured together forms a bore extending the greater portion of the length of the handle. The portions 11 and 12 of the handle are secured together by any suitable means as by 35 the screw 14. Secured to one end of the section 11 of the handle by means of one of the screws 14 which hold the sections together, is one end of a metallic strip 15 which is 40 bowed into a loop 16 and has its other end passed through an inclined slot 17 in the section 12, near the adjacent end, and then passed through the bore formed by the channels 13. Formed through the section 12 of 45 the handle is an elongated slot 18 through which extends the outturned terminal hand grip 19 of the strip 15. Secured to one end of the handle is a band 20, in which is mounted a set screw 21, the end of said 50 set screw passing through the section 12 and being adapted to engage against the strip 15 which is located within the bore formed by the channels 13, to hold said strip in different positions accordingly as the same is 55 moved by means of the hand grip 19. Se-

cured to the handle is a plate 22 having the outwardly flared arms 23, for engagement with the body of the cuspidor to prevent sidewise movement of the same when gripped within the loop 16. To the under 60 face of this end of the handle and slightly remote from the end is an angle plate 24 the arm 27 of which is provided with an elongated slot 25 to receive one end of the screw 24', on which is a clamping nut 26 for 65 adjusting the said plate longitudinally on the handle. When a cuspidor is held within the loop 16, the tendency would be for the cuspidor to sag toward the end of the handle, but the presence of the arm 27' of the angle 70 plate prevents such sagging, by acting as a stop against which the side of the bowl portion of the cuspidor engages. Secured to the flat face of the section 11 of the handle, is a small plate 28, against which the strip 75 15 bears and prevents the point of the screw 21 from denting the flat strip 15 and the consequent denting of the flat face of the section 11.

What is claimed is:

A lifter and carrier for cuspidors comprising a handle, said handle being formed of two sections, each of which is formed with a longitudinal channel, one of said sections being formed with an elongated slot and an 85 inclined passage, a flexible metallic strip secured at one end to one end of one of said sections, the opposite end portion of said strip extending through the inclined passage and through the said channel, a terminal hand grip on the free end of said strip and projecting through said elongated slot, a band encircling one end of said handle, a set screw on said band for engagement with the said strip to hold the same in its 90 different adjusted positions, an outwardly and downwardly extending member on the end of said handle for engagement with a cuspidor to prevent lateral movement of the same when engaged in the loop, and an adjustable member on the loop carrying end of the handle for engagement with the bowl portion of the cuspidor.

In testimony whereof I affix my signature, in the presence of two witnesses.

ERNEST OLD.
